UNITED STATES PATENT OFFICE.

HARVARD F. WESTON, OF NEWTON CENTER, MASSACHUSETTS.

HEEL LINING FOR REPAIRING SHOES.

1,418,855.

Specification of Letters Patent. Patented June 6, 1922.

Application filed January 12, 1921. Serial No. 436,659.

To all whom it may concern:

Be it known that I, HARVARD F. WESTON, a citizen of the United States, residing at Newton Center, in the county of Middlesex 5 and State of Massachusetts, have invented a new and useful Improvement in Heel Linings for Repairing Shoes, of which the following is a specification, reference being had therein to the accompanying drawings.

10 My invention relates to heel linings for boots and shoes and more particularly to a heel lining adapted to be sold as a commercial article for use in repairing boots and shoes.

15 In repairing shoes, it is frequently found necessary to renew the lining of the shoe at the heel since the friction between the heel portion of the foot and the lining of the shoe causes a rapid wearing out and de-

20 terioration of that portion of the shoe. For some time heel linings for use in repairing shoes have been made and sold to repairers as a commercial product. These linings have generally been made of a heel seat or 25 pad, semi-circular at its heel end, and an upright back or counter portion secured to the heel seat by stitching or adhesive; the latter portion being approximately semi-circular in plan with a straight edge which 30 is secured to the heel seat. The use of heel linings so made has, however, been open to various objections. In the first place, it is practically impossible to make such a heel lining fit the heel portion of the shoe, since 35 shoes are all made on lasts having the heel portions corresponding in shape to the shape of the heel of the wearer. The back of the heel of the shoe is, therefore, not a straight line from the sole upwardly, but a curve, 40 bulging out rearwardly of the shoe, and a heel lining which is straight from the heel seat to the top of the back or counter portion will not fit this concavity. In the second place, the shape of the back or counter 45 portion of the heel lining prevents it being permanently fastened in the heel of the shoe and this is especially true of oxford shoes. Where the upright back or counter portion of the heel lining is curved it can 50 be secured to the shoe for a short distance only at the back of the heel since any stitching which followed the outline of the back of the lining, would disfigure the outside of the heel portion of the shoe. Being fas- 55 tened, therefore, only at the extreme rear,

the unsecured curved edges of the back or counter portion of the lining tends to curl or roll over after the shoe has been worn a short time, causing more or less discomfort to the wearer.

60 The main object of my invention is the provision of a heel lining for use in repairing shoes which is so made that it will fit naturally and smoothly into the concavity of the heel of the shoe without requiring stretching or other manipulation.

Another object of the invention is the provision of a heel lining so shaped that it may be securely fastened in the shoe in such a manner as to prevent the wrinkling or curling of the edges.

70 Other objects of the invention will be more specifically described and pointed out hereinafter.

One of the important features of my invention resides in providing a heel lining in which the back or counter portion is normally at an acute angle to the heel seat so that the rear curved portion of the heel lining projects rearwardly with the counter 75 portion slanting inwardly over the heel seat. I have found that when a heel lining of this shape is placed in the heel portion of a shoe, it will fit the concavity which receives the heel of the wearer naturally and without 80 requiring stretching or other manipulation to secure smoothness and a perfect fit. This shape of the heel lining may be secured in various ways but I prefer to accomplish it by having the lower edge of the back or 85 counter portion before it is united to the heel seat curved outwardly and upon the amount of this outward curve will depend the 90 inward slant of the counter portion in the finished lining.

95 Another feature of my invention consists in providing a heel lining adapted to have its entire upper edge secured within the shoe by stitching coinciding with the stitching which secures the rear part of the vamp 100 to the upper. By means of this construction, I am enabled to make the ends of the counter portion straight so that after the heel lining has been fastened within the shoe, each of the end edges of the counter 105 portion makes a straight line between the stitching at the top of the heel lining and the heel seat. This prevents any curling or wrinkling of these edges after the shoe has been worn.

- In the drawings illustrating the preferred embodiment of my invention, Figure 1 is a view in perspective of a heel lining constructed in accordance therewith; Fig. 2 is a plan view of the back or counter portion of the heel lining or of a pattern for cutting the same; Fig. 3 is a similar plan view of the heel seat or of a pattern for cutting the heel seat; Fig. 4 is a plan view of the heel lining shown in Fig. 1, bottom uppermost; Fig. 5 is a central, longitudinal, vertical sectional view of the heel portion of a shoe having a repair heel lining constructed in accordance with my invention arranged therein preparatory to being fitted to the heel portion of the shoe and permanently secured therein and Fig. 6 is a similar view showing the heel lining fitted to said heel portion and permanently secured in position.
- 20 In the drawings illustrating the preferred form of my invention is shown a heel lining made up of a heel seat 5 and a back or counter portion 6, the heel seat being of usual construction, as shown in Figure 3.
- 25 The back or counter 6 may be substantially rectangular in form, as shown, with its longitudinal edge 7 curved slightly outwardly and with its upper longitudinal edge straight or curved inwardly in parallelism with the lower edge 7. The two ends 9 and 10 are straight and may be either perpendicular to the lower edge or slanted in relation to the same. To facilitate the attaching of the back or counter 6 to the heel seat 5 the lower edge of the counter may be provided with a series of triangular notches 12-12.
- 30 In making my heel lining the heel seat 5 and back or counter portion 6 are cut out from leather or other suitable material in the forms shown in Figs. 3 and 2 respectively, by the use of suitable patterns. The back or counter portion 6 is then secured to the heel seat as shown in Fig. 4 by turning the lower edge 7 of the back or counter portion over upon the bottom of the heel seat 5 and securing the edge thereto by the use of adhesive or other suitable means. The heel lining is then ready for use.
- 35 40 In Figs. 5 and 6 of the drawings is illustrated the method of applying to a shoe a repair heel lining constructed in accordance with my invention. In those figures I have shown the heel portion of a shoe comprising quarters 14, a heel 16, a sole 18 and a sole lining 20, all of the usual and well known construction, the usual stitching at the top of the vamp being designated as 22. When a new heel lining is required in repairing a
- 45 50 shoe, one of my linings is placed in the heel portion of the shoe as shown in Fig. 5. It will be observed from this figure that the extreme rear or heel portion 24 of the shoe curves inwardly toward the toe over the heel 16 so that as the heel lining is first

placed loosely in the heel portion of the shoe the forward slant of the counter-portion 6 of the heel lining follows naturally the forward slant of the portion 24 of the vamp. After the heel lining is placed in the shoe 70 it is fitted around the inner surface of the heel of the shoe with the fingers and then assumes the position shown in Fig. 6 of the drawings. Owing to the fact that the counter-portion 6 is normally at an acute 75 angle to the heel seat 5 around the curved portion of the heel seat, a fullness is created on that portion which permits the lining to assume the form shown in Fig. 6 and to fit closely the curved portion 24 of the shoe. After the lining has been fitted to the heel portion of the shoe, the heel seat may be cemented, if desired, to the lining 20, although this is not absolutely required, and it is then permanently secured in the shoe 80 by stitching 26 coincident with the vamp stitching 22. The surplus top portion of the heel lining may then be trimmed off around the top of the vamp and the operation is completed. 85

90 It will be noticed that my heel lining, after it has been fitted into the concavity of the heel of the shoe, will retain that form because of its fullness in that portion so that not only is a better fit of the heel lining of the shoe secured, but less time and labor are consumed in attaining this result. At the same time, the comfort of the wearer is assured by the fact that the lining fits the shoe smoothly and is free from wrinkles. 95

100 My heel lining can be made to fit any style of shoe since the acute angle between the counter-portion and the heel seat is controlled by the amount of curvature on the lower edge of the counter-portion and, therefore, the projection of the heel lining rearwardly may be increased or decreased by decreasing or increasing the radius of this curve. 110

115 By making the upper edge of the back or counter portion 6 substantially at right angles with the two ends 9 and 10 and then securing the back or counter portion to the shoe by stitching along the entire edge 8, I avoid the curling or folding over of the edge which is a common objection to the use of heel linings in which the back or counter portion has a curved edge extending from the heel seat on one side to the other side. 120 In my lining it is not necessary to secure the ends 9 and 10 to the shoe since both edges are straight lines, each secured at the bottom to the heel seat and at the top of the shoe by the stitching. Therefore any 125 rolling or curling of these edges is practically impossible.

130 It will be observed that one of the most important features of my invention, and one contributing largely to the advantageous

results which I secure, is in having the lower longitudinal edge of the back or counter portion convex or curved outwardly. Although in the preferred form the convexity 5 of this lower edge is preferably secured by a curve, yet it is within the scope of my invention to attain this end by two straight lines running outwardly away from a straight line connecting the two ends of said lower edge and meeting in the centre. Where the convexity of the lower edge is secured in this manner and the lower edge 10 is broken up by notches to facilitate the curve of the back portion around the rear end of the heel seat, the result attained is 15 almost the same as by a convex curve.

Although I have shown the back or counter portion 6 substantially rectangular in plan it is to be understood that I am not 20 to be limited to this exact form since it may be of any form which will present an upper edge adapted to be secured to the shoe coincident with the vamp stitching so that the ends are straight.

What I claim is:—

1. A heel lining comprising a heel seat and a counter portion secured at its lower edge to said heel seat; said counter portion being normally at an acute angle to said heel seat along the curved edge of said heel 25 seat.

2. A heel lining comprising a heel seat and a counter portion; said counter portion being normally at an acute angle to said heel seat at the rear portion thereof and having 30 a straight upper edge adapted to be stitched to the shoe coincident with the vamp stitching.

3. The combination with a boot or shoe of a repair heel lining arranged in the heel 40 portion of said boot or shoe over the usual lining; said repair lining having a straight upper edge stitched to the upper of said boot or shoe by stitching substantially coincident with the vamp stitching.

In witness whereof, I hereunto set my hand this eighth day of January, 1921.

HARVARD F. WESTON.
